[57] CLAIM

The ornamental design for a combined beverage cup and holder, as shown.

DESCRIPTION

FIG. 1 is an elevational front view of the combined beverage cup and holder according to my design.

FIG. 2 is an elevational left view thereof.

FIG. 3 is an elevational right view thereof.

FIG. 4 is a perspective front view thereof.

FIG. 5 is an elevational view of the beverage cup of FIG. 1.

FIG. 6 is a top view thereof.

FIG. 7 is an elevational front view of the holder of FIG. 1.

FIG. 8 is a top plan view of the holder of FIG. 1.

FIG. 9 is a bottom view of the holder of FIG. 1.

FIG. 10 is a front elevational view of another modification of the combined cup and beverage holder of FIG. 1.

FIG. 11 is a front elevational view of another modification of the combined beverage cup and holder of FIG. 1.

FIG. 12 is an elevational view of another modification of the combined beverage cup and holder of FIG. 1.
